UNITED STATES PATENT OFFICE

CARL C. IRWIN, OF KIRKWOOD, MISSOURI, ASSIGNOR TO ELY & WALKER DRY GOODS COMPANY, OF ST. LOUIS, MISSOURI, A CORPORATION OF MISSOURI

DESIGN FOR A MERCHANTISE-DISPLAY CABINET

Application filed September 5, 1930. Serial No. 36,882. Term of patent 7 years.

To all whom it may concern:

Be it known that I, CARL C. IRWIN, a citizen of the United States of America, residing at Kirkwood, county of St. Louis, State of Missouri, have invented a new, original, and ornamental Design for a Merchandise-Display Cabinet, of which the following is a specification, reference being had to the accompanying drawing, forming part thereof.

The figure is a perspective view of the display cabinet embodying my design.

I claim:

The ornamental design for a merchandise display cabinet, as shown.

CARL C. IRWIN.
